UNITED STATES PATENT OFFICE.

CLAYTON TRIDLE ULREY, OF EAST ORANGE, NEW JERSEY, ASSIGNOR TO WESTINGHOUSE LAMP COMPANY, A CORPORATION OF PENNSYLVANIA.

DESTRUCTION OF THE ELECTRICAL CONDUCTIVITY OF FILMS.

No Drawing. Application filed January 3, 1923. Serial No. 610,526.

This invention relates to evacuated electrical devices and more particularly to methods of destroying the electrical conductivity of films between leading-in wires 5 or electrodes sealed therein.

An object of my invention is the provision of a method for salvaging evacuated electrical devices, for example, radio tubes, which have been short-circuited by a deposit of conductive material on the press, 10 between two or more leading-in wires thereof.

Another object of my invention is the elimination of conductive films, which may 15 be deposited between the leading-in conductors of evacuated electrical devices, thereby causing short circuits, by subjecting such films to electrical treatment to destroy their electrical conductivity.

20 A further object of my invention is the destruction of short-circuiting films or deposits of clean-up or getter material, which may have been formed on the press of a radio bulb or the like, by subjecting the same to an electrical discharge.

25 A still further object of my invention is the treatment of evacuated electrical devices, for example, radio bulbs, which have been rendered inoperative because of the formation of a conductive film of clean-up 30 or getter material on the press between the leading-in wires to the grid, plate and filament, to restore them to their operative condition by destroying the electrical conductivity of such film by an electrical discharge.

35 Other objects and advantages of the invention will become apparent upon reading the following detailed description.

40 For cleaning up residual gases in evacuated electrical devices, for example, radio tubes, it has become very common to use a metallic clean-up material such as aluminum, magnesium, calcium or the like. Such material may be fastened to or deposited on the plate of such a radio bulb and activated 45 or vaporized by heating said plate to such temperature as to vaporize the clean-up material, in whole or in part, until the required degree of vacuum is obtained in the bulb.

50 In order to be sure of properly eliminating residual and electrode-occluded gases, an excess of clean-up material is used in practice. If the clean-up material is vaporized to a greater extent than that which will combine with such gases, which is the usual

case, a film or mirror of metallic material will be deposited on the inner wall of the bulb. It is desirable to so restrict such film or mirror as not to interfere with the proper observation of the filament when the tube 60 is in operation and not to cause short-circuiting between leading-in conductors.

It has been found, in practice, that such mirror may be so restricted as to leave a portion of the bulb surface free for the 65 proper observation of the interior thereof, but it is not always possible to prevent some of the material from depositing on the press between leading-in conductors, thereby short-circuiting or providing a conductive path between said conductors and rendering the tube inoperative. Prior to my invention, radio bulbs, short-circuited as aforesaid, were considered worthless 70 and, consequently, were scrapped. According to my invention, I have devised a convenient, simple and efficient method of salvaging such tubes by destroying the electrical conductivity of short-circuiting films 75 therein by electrical means. 80

My method of destroying the conductivity of such films comprises connecting the leading-in wires of the device momentarily to a single wire or terminal of a source of high-potential and preferably high-frequency current. The same apparatus used for vaporizing the metallic clean-up agent, which formed the undesirable short-circuiting film on the press of the radio bulb, may also be used for destroying the conductivity 85 of such film. That is, the lead wires of the device may be connected to one terminal of the source of high-frequency current which was used for vaporizing or activating the metallic clean-up agent employed. The 90 treatment is accomplished in a few seconds without the use of any accessory apparatus. 95

Although it is not definitely known how such treatment affects a metallic film to render it non-conductive, it is thought that the 100 effect is like a mechanical disintegration of the film and is not the result of any purely heating action because of a current passed therethrough. The current passing through the film by such treatment is principally 105 due to the capacitance of the device being treated and apparently too small to cause any appreciable vaporization of the metallic material. The film on the press and interior 110 of the bulb apparently serves as a plate of

a condenser, thereby permitting a charging current to surge back and forth, to and from the film and by causing large differences and quick changes in the electrostatic attraction 5 and repulsion between the film and the glass on which it is deposited, effects a mechanical loosening of the film from the glass and disintegration of the various portions of the film. This results in rendering a film substantially non-conductive of electricity, although the treatment does not cause any appreciable change in the appearance of the film.

Although I have attempted to explain the 15 effect of the proposed treatment, I do not wish to be limited to the theory advanced in connection therewith, the main point being that, according to my invention, I may render non-conducting any metallic 20 films deposited on the portion of an evacuated electrical device, through which leading-in conductors are sealed, in an efficient, convenient and rapid manner by the application of high-frequency, high-potential current thereto, without effecting any material 25 change in the appearance of the film.

After treatment according to my invention, the device so salvaged may be used for the purpose for which it was normally intended, just as if no short-circuiting film 30 had been formed thereon.

Although I have described what I now consider the preferred embodiment of my invention, it is to be understood that the 35 same is merely illustrative and that my in-

vention may be used for destroying the electrical conductivity of such undesirable conducting films between leading-in wires in any evacuated device, without departing from the spirit and scope of the appended 40 claims.

What is claimed is:

1. The method of destroying the electrical conductivity of a film of metallic material comprising impressing intermittent high 45 voltage thereon.

2. The method of increasing the resistance of an electrically conductive film formed between leading-in wires in an electrical device comprising impressing intermittent 50 high-potential electricity thereon.

3. The method of salvaging evacuated electrical devices which have been rendered inoperative because of a film of clean-up material deposited between leading-in conductors comprising connecting said leading-in conductors to one terminal of a source of intermittent high-potential and thereby destroying the electrical conductivity of said film and rendering the device suitable for 55 normal use.

4. The method of destroying the conductivity of a film of metallic clean-up material in an evacuated electrical device comprising connecting said film to a source of high-frequency, high-potential current.

In testimony whereof, I have hereunto subscribed my name this second day of January, 1923.

CLAYTON TRIDLE ULREY.
